Patented Jan. 18, 1921.

UNITED STATES PATENT OFFICE.

CHARLES A. GOOZEY, OF PROVIDENCE, RHODE ISLAND.

SLIDE-RING.

1,365,911.

Specification of Letters Patent.

Patented Jan. 18, 1921.

Application filed August 4, 1919. Serial No. 315,072.

To all whom it may concern:

Be it known that I, CHARLES A. GOOZEY, a citizen of the United States, and resident of Providence, in the county of Providence and 5 State of Rhode Island, have invented certain new and useful Improvements in Slide-Rings, of which the following is a specification.

This invention relates to so-called slide 10 rings of the class more particularly adapted to be used as connecting members for the ends of chains for personal wear; one object of this invention being to so construct the ring that no spring will be required to 15 operate the parts. Another object is to construct the outer tubular ring with an opening therethrough and to provide an inner ring or member slidably mounted in the outer ring and having a portion shaped to 20 form a loop or recess for the purpose of receiving the so-called jump ring or end link of a chain, said loop or recess being adapted to be closed by the wall of the outer ring when moved from registration with the 25 opening, thereby securely locking the jump ring in the slide ring.

A further object of the invention is the provision of means in the inner ring whereby the two ends of the outer ring are supported against being moved out of lateral alignment even when in open position.

A still further object of the invention is to provide means for locking the inner or slide ring in adjusted position in the outer 35 ring.

With these and other objects in view the invention consists of certain novel features of construction, as will be more fully described and particularly pointed out in the 40 appended claims.

In the accompanying drawings:

Figure 1— is a sectional side elevation showing the loop in the slide ring as registering with the opening in the outer ring 45 forming an open loop to receive the jump ring or chain link.

Fig. 2— shows the slide ring as moved out of registration with the opening in the outer ring thereby securely locking the jump 50 ring to the slide ring.

Fig. 3— is an enlarged section on line 3—3 of Fig. 1, showing the end of the outer ring and the looped portion of the inner ring in section.

Fig. 4— is a sectional end view of the

outer ring, showing the same as slotted through its inner surface.

Fig. 5— is a detail of the inner slide ring.

Fig. 6— is a perspective view showing 60 the looped portion as extending through the inner slot of the outer ring.

Referring to the drawings, 10 designates the outer tubular ring which is preferably slotted as at 11 through its inner surface 65 and has a portion removed as at 12 forming an entering mouth thereinto.

The essence of my present invention is the particular form or construction of the inner or slide ring 13 which may be bent or otherwise shaped either of wire or flat stock into circular form, one portion of the circle being offset inwardly or toward the center of the ring forming a loop having an open mouth 14. This loop is flattened as at 15, 75 see Fig. 3, to be of less thickness than the rest of the ring so that it will extend through and slide freely in the relatively narrow slot 11 through the inner circumference of the outer ring. The adjacent ends 80 16 of the wire are preferably offset slightly, in a lateral direction so that when this inner ring is positioned in the outer ring the inherent spring of the metal of the inner ring will serve as a friction to retain the inner 85 ring in adjusted position to the outer ring.

As a further means of retaining the inner ring in adjusted position I have provided a protuberance 17 on this inner ring, which will engage the edge of the outer ring when 90 the loop of the inner ring is moved to closed position.

By my improved construction of inner ring adapted to slide within the outer ring, I have obtained a number of advantages 95 over the old style construction where a spring is employed for returning the slide ring to closed position; first, by eliminating the spring from this outer ring the tubing may be made very much smaller than could 100 possibly be the case where the coil spring is employed, owing to the fact that there is a limit to the smallness of size of the coil spring. This feature is of considerable advantage as the smaller the tubing the smaller 105 may be made the jump ring or end link 19 of the chain 20 necessary to be passed into the ring over this tubing; second, where the spring is eliminated the slide ring is much easier to operate as with the spring the slid- 110

ing member must be held open by the hand of the user against spring pressure while the jump ring is being positioned therein, while with my improved device the inner 5 ring will stay wherever positioned; third, my improved construction of inner or slide ring having an inwardly extending loop member serves to materially strengthen the outer ring as at no time are the ends of the 10 outer ring left free but are always retained in alinement by the inner ring and so prevented from lateral displacement; fourth, another advantage of this invention is that as the wire of the inside ring 13 is greater in 15 diameter than the width of the circular slot 11 through the inner surface of the outer ring or shell, this inside member serves as a lock to prevent spreading or separating of the opening through the outer ring when 20 under excessive strain. By extending the loop of the inner ring inwardly or toward the center of the circle this loop is protected against being moved by contact with any outside object.

25 Another feature of this invention is that when a link of the chain is passed into the recess in the inner ring, it engages the side wall of this recess and any tension on the chain tends to exert a relative rotating motion to the inner ring when the outer ring 30 is retained by its support 18 causing the inner ring to rotate and close the mouth of the outer ring, and every pull or tension exerted in opposite directions on opposite 35 portions of the chain tends to move and hold the inner ring in closed or locked position.

In operating this device it is only necessary to engage the eye 18 with one hand and then with the other hand place the jump 40 ring 19 on the end of the chain 20, shown in dotted lines, into the open mouth 14 of the loop in the inner ring as shown in Fig. 1, then carry the chain downwardly around the outer ring into the position illustrated in 45 Fig. 2, which slides the inner ring within the outer ring causing the wall of the outer ring to close the open mouth 14 of the loop thus bringing the stop 17 out into the open between the ends of the outer ring and thereby locking the inner ring in position 50 to firmly secure the link of the chain thereto.

The foregoing description is directed solely toward the construction illustrated, but I desire it to be understood that I reserve the privilege of resorting to all the 55 mechanical changes to which the device is susceptible, the invention being defined and limited only by the terms of the appended claims.

60

I claim:

1. A chain connector for personal wear, comprising an outer tubular ring having an opening thereto, an attaching member on the periphery of said ring, said ring having an annular slot through its inner wall, an 65 inner wire ring slidably mounted in said outer ring and having a portion bent to form an inwardly-extending loop the same being opened to the outside when positioned opposite the opening in said tube and closed by 70 said tube when moved out of registration with said opening said loop extending inwardly through said slot to slide therein.

2. A chain connector for personal wear, comprising an outer tubular ring having an 75 opening through it, said ring being provided with an annular slot through its inner surface, an inner ring slidably mounted in the hollow center of said outer ring and having a portion of its circle offset inwardly to form 80 an open mouthed inwardly extending loop slidable in said slot, the mouth of said loop being adapted to register with the opening in said outer ring to receive the connecting member and closed by moving the openings 85 in each out of registration with each other.

3. A chain connector for personal wear, comprising an outer tubular ring having an opening thereto said ring being slotted circularly through its inner surface, an inner 90 wire ring slidably mounted in said outer ring and having a portion bent to form an inwardly extending loop extending through and slidale in said slot, said loop being open on one side when registering with the 95 opening in said outer ring and closed when moved out of registration with said opening, and means for retaining said inner and outer rings in relative adjusted positions.

In testimony whereof I affix my signature. 100

CHARLES A. GOOZER
